CLAIM

The ornamental design for an outdoor camera, as shown and described.

DESCRIPTION

FIG. 1 is a top view of a first embodiment of an outdoor camera showing the design;

FIG. 2 is a perspective view thereof;

FIG. 3 is a front view thereof;

FIG. 4 is a left side view thereof;

FIG. 5 is a right side view thereof;

FIG. 6 is a rear view thereof;

FIG. 7 is a bottom view thereof;

FIG. 8 is a top view of a second embodiment of an outdoor camera showing the design;

FIG. 9 is a perspective view thereof;

FIG. 10 is a front view thereof;

FIG. 11 is a left side view thereof;

FIG. 12 is a right side view thereof;

FIG. 13 is a rear view thereof; and,

FIG. 14 is a bottom view thereof.

The broken lines in Figures are for illustrative purposes only and form no part of the claimed design.
